UNITED STATES PATENT OFFICE

MARSHALL T. BREKKE, OF SCARSDALE, NEW YORK, ASSIGNOR TO NORTHAM WARREN CORPORATION, OF NEW YORK, N. Y., A CORPORATION OF NEW YORK

DESIGN FOR A BRUSH

Application filed December 13, 1930. Serial No. 37,975. Term of patent 14 years.

To all whom it may concern.

Be it known that I, MARSHALL T. BREKKE, a citizen of the United States, residing at Scarsdale, in the county of Westchester and State of New York, have invented a new, original, and ornamental Design for Brushes, of which the following is a specification, reference being had to the accompanying drawing, forming part thereof.

Fig. 1 is a side elevation of a nail brush embodying my new design.

Fig. 2 is a plan view of the top of such brush.

Fig. 3 is an end elevation of the same.

I claim:

The ornamental design for a brush substantially as shown.

MARSHALL T. BREKKE.
